UNITED STATES PATENT OFFICE

CHARLES B. GILMORE, OF CHICAGO, ILLINOIS, ASSIGNOR TO CHICAGO FORGING & MANUFACTURING COMPANY, OF CHICAGO, ILLINOIS, A CORPORATION OF ILLINOIS

HOOD LATCH

Application filed March 9, 1928. Serial No. 260,326.

My invention relates to a latch for closures and particularly to a hood latch adaptable for holding down the lower edges of hoods used for automobiles. One object of my invention is to provide such a latch which shall be simple and cheap to make and efficient and durable in use. Another object is to provide such a latch which shall thrust the edge of the hood inwardly as well as downwardly. Another object is the manufacture of such a hood latch in which the latch itself shall carry a minimum number of projections or extensions. Other objects will appear from time to time in the course of the specification and claims.

I illustrate my invention more or less diagrammatically in the accompanying drawings, wherein—

Figure 1 is a side elevation of one form of my device;

Figure 2 is a section on the line 2—2 of Figure 1;

Figure 3 is a section on the line 3—3 of Figure 2;

Figures 4 and 5 are details;

Figure 6 is a view similar to Figure 2 of a variant type;

Figure 7 is a partial plan view;

Figure 8 is a section on the line 8—8 of Figure 6;

Figure 9 is a side elevation of a third form of my device;

Figure 10 is a section on the line 10—10 of Figure 9; and

Figure 11 is a section on the line 11—11 of Figure 10.

Like parts are indicated by like symbols throughout the specification and drawings.

Referring first to Figures 1 to 5 A generally indicates the automobile frame member to which the hood latch is attached. A¹ is a flange or abutment upwardly projecting thereagainst and A² represents the lower portion of the hood closure, the lower edge A³ of which outwardly overlaps the flange A¹ and is thrust thereagainst by the hood latch mechanism below described.

B generally indicates a hood latch base member herein shown as having the lateral extensions B⁴ locked in position on the mem-

ber A for example by the bolts B². B³ is a central raised portion apertured as at B⁴ and downwardly depressed about such aperture as at B⁵. It will be seen for example from Figure 2 that the top of the member B³ is 55 downwardly and outwardly inclined.

Swivelled in the aperture B⁴ is the latch pin C having at its bottom the head, preferably a square head C¹, which limits it against any substantial arc of rotation by its engagement with the sides of the base member B. The pin C is headed at the top as at C², the upper portion penetrating the latch cylinder proper C³ with its apertured bottom member C⁴. Compressed between the head of the 65 pin C² and the member C⁴ is a coil spring C⁵ which normally tends to thrust the latch cylinder C³ downwardly along the pin C. C⁶ indicates a handle member secured to the top of the latch and C⁷ a lateral extension, lug or 70 the like, preferably but not necessarily integral to the handle and herein shown as terminating in a cross piece C⁸.

D indicates a cam member mounted upon the hood A² and secured thereto as by the 75 rivets D¹. It is provided with an upward forked extension generally shown as D² the central aperture D³ of which is transversely enlarged as at D⁴. The upper portion of the aperture D³ is of such width as to admit 80 the member C⁷ of the latch and the members D² are sufficiently widely spaced from the hood A² to permit the penetration therebetween of the cross piece C⁸.

Slidably mounted in the enlargement D⁴ 85 is a member generally indicated as E, shown for example in Figure 5 which includes the central stem E¹ which passes through the aperture D⁴, the cross piece or head E² too broad to pass therethrough and the lower enlargement or extension E³ downwardly and outwardly inclined from the stem E¹ adapted to rest upon the cam member D.

In operation the hood latch is manually 95 raised until the cross-piece C⁸ clears the tops of the members D² and is then dropped into the position in which it is shown in Figure 2. The cross-piece C⁸ then engages the cross-piece E² and thrusts the member E downwardly and outwardly across the cam surface 100

D and into contact with the latch cylinder C³. It will be clear from the drawing that the spring C⁵ not only thrusts the latch downwardly along the pin C but also thrusts the member E downwardly across the cam D. The resultant cam action directs pressure outwardly against the central or lower portion of the latch C³ by means of the engaging lower portion E³ of the member E. Stated otherwise, the result, since the hood latch C³ cannot move outwardly away from the closure, is the direction of pressure inwardly as well as downwardly against the closure A² and a peculiarly snug fit is insured, with a minimum of looseness or rattling.

When the hood latch is removed the member E cannot be lost since, as clearly shown in Figure 4 the size of the parts is such that the member E cannot escape from the aperture D⁴, having the head E² at one end of the stem E¹ and the enlargement E³ at the other.

Referring to Figures 6, 7 and 8 a variant form is provided, in which in the place of the cam D and the member E a lever G is mounted upon the closure A², being pivoted to the outwardly projecting bearing member G¹.

The upper arm of the lever is curved upwardly and inwardly toward the closure A², as shown at G² in Figure 6 and is provided with an enlarged cross piece G³ at its top. The lower arm of the lever is downwardly and outwardly inclined as at G⁴ and terminates at its bottom in a cross piece G⁵ adapted to engage the lower portion of the latch cylinder C³.

Extending above the supporting member G¹ are the two prongs G⁶ with the aperture G⁷ between them of sufficient size to admit the projection C⁷ from the hood latch handle. The cross piece G⁸, when the hood latch is in operative position, is interposed between the upper arm G² of the lever and the prongs G⁶ and therefore tends, in response to the action of the spring C⁵, to rotate the lever in counter-clock-wise fashion, as shown in Figure 6 and thus to direct pressure outwardly against the lower end of the cylinder C³ and, since the cylinder C³ cannot move outwardly, to cause a resultant inward pressure against the lower edge of the closure A².

When the latch is released the lever G must remain in operative position, in position to receive the cross bar C⁸, since the head G⁸ is too broad to pass through the aperture G⁷. It will thus always be found easy to drop the latch into place.

Referring to Figures 9, 10 and 11 a support H is mounted upon the closure A² and in it is slidably positioned a member generally shown as H¹. It includes a downwardly and outwardly inclined portion H² terminating in a re-curved end H³ adapted to engage the latch cylinder C³. Its lower portion C² is

provided with laterally extending lugs H⁴ passing through cam slots H⁵ in the sides of the member H. The intermediate portion of the member H¹ is provided with lateral lugs H⁶ extending outwardly through generally vertical guide slots H⁷ in the sides of the member H. The member H¹ terminates at its upper end in an upwardly and outwardly inclined extension H⁸ which is forked at its upper end as at H⁹ to receive an extension H¹⁰ from the handle of the latch. A cross piece H¹¹ holds the latch in position once it has engaged the knob or fork H⁹.

The operating effect of the form of Figures 9, 10 and 11 is the same as that of the earlier forms, in that downward pressure directed by the top of the hood latch results in lateral pressure directed against the lower portion of the hood latch, and thus against the lower edge of the closure A². In the form last described the cam action is provided, instead of the lever action of the second form.

It will be realized that whereas I have described a practical and operative device nevertheless many changes might be made in the size, shape, number and disposition of parts without departing from the spirit of my invention. I therefore wish my description and drawings to be taken as in a broad sense illustrative and diagrammatic rather than as limiting me to my specific showing.

I claim:

1. In a latch for a closure, a base to which said latch is secured, a latch guide mounted upon said base, a latch body movable upon said guide, yielding means tending normally to move it downwardly along said guide, a member at the upper end of said latch body adapted to engage the closure and to direct pressure downwardly thereagainst and means, mounted between closure and latch, adapted to direct pressure inwardly against said closure in response to the downward pressure exerted by said latch, said means including a member slidably mounted upon said closure.

2. In a latch for a closure, a latch body and means for imparting downward movement thereto, means at the upper end of said latch body for engaging the closure and for directing pressure downwardly thereagainst in response to downward movement of the latch body and means interposed between closure and latch, for translating the downward pressure exerted by the upper portion of said latch body into inward pressure against said closure, including a member slidably mounted upon said closure.

Signed at Chicago, county of Cook and State of Illinois, this 3rd day of March, 1928.

CHARLES B. GILMORE.
